FAY T. RODGERS, OF MEMPHIS, TENNESSEE.

REFRIGERATOR.

Application filed August 2, 1926. Serial No. 126,436.

This invention relates to refrigerators designed for cooling by means of ice or other similar refrigerant and has especial relation to the shape, arrangement, disposition and means of securing the refrigerant container within the refrigerator and to means for taking care of the drainage from such container.

It is of extreme importance in refrigerators, that the refrigerant be placed where it will do the most good, that the moisture condensing on the outside of the container be suitably collected, as well as, that where ice is used, the water formed by the melting ice be properly taken care of, in order that the body of the refrigerator or what may be designated as the "food storage portion" be kept as free from moisture as possible.

It is of further importance that advantage be taken of every opportunity to bring the air within the refrigerator in contact with the cooling medium, and that as large a proportion of the length of the refrigerator as possible be available for use as storage space.

The objects of this invention, are,

(a) To provide means for exposing a maximum surface of the refrigerant container to the air;

(b) To provide means for presenting the surface of the refrigerant container to the direct action of the warmest air in the refrigerator;

(c) To provide simple and efficient means for collecting the moisture of condensation on the exterior surface of the container;

(d) To provide means for leading or draining off the condensation moisture and the water from the melted ice in a simple and efficient manner;

(e) To provide as great visibility of the storage space as possible, and

(f) To generally improve and simplify the details of construction of the refrigerant container and drains.

The means by which these and other objects are accomplished, and the manner of their accomplishment will readily be understood from the following description on reference to the drawings, in which,—

Fig. 1 is a sectional elevation of the refrigerator at right angles to its length, taken on the line I—I of Fig. 2.

Fig. 2 is a longitudinal sectional elevation

along the longitudinal center line of the refrigerant container, looking in the direction of the arrow, (Fig. 1) and showing slightly more than one-half of the length of the particular refrigerator used as an illustration.

Fig. 3 is a fragmentary detail showing one method of supporting one side of the refrigerant container.

Fig. 4 is a similar detail showing a second method of supporting the container.

Referring now to the drawings, in which the various parts are indicated by numerals, the refrigerator selected for illustration is one having the usual insulated bottom 1, a front having a double glass panel 2, with a plurality of upper doors 3 and lower doors 4, at the rear to provide access to the storage portion of the refrigerator. Preferably the doors 3 are made with double glass panels whereas the doors 4 are of construction similar to the bottom of the case. The interior of the case may have the usual sheet metal lining 5. The top of the case is preferably of insulated construction 6 having doors 7, similarly insulated, for the introduction of the refrigerant thereinto. In the present case, only one, of two doors, is shown, though three or even more such doors might be used should it be deemed necessary.

Disposed longitudinally of the refrigerator and extending substantially the entire length thereof, is a refrigerant container 8 which may be a single continuous trough or may be a trough made up of a number of sections 8, 8^A, 8^B, etc. In Fig. 1 this trough is shown of triangular cross section. In Fig. 3 the fragmentary sectional part thereof shown, indicates that it may be of curved cross section, such for instance as half-round or some intermediate section between half-round and V-shaped.

The container is provided with a plurality of drain openings 9 at or near the bottom thereof, and preferably with openings 10 adjacent the point of support, to permit air circulation. Should it be found necessary, where the openings 10 are not placed at the lowest point of the container, additional openings 11 may be so placed and at such intervals as may be desired. Each end section of the container preferably is provided with an end 12 which preferably, does not extend upward against the underside of the refrigerator top, so that an air space 13 is

left between the top of these end walls and the under surface of the refrigerator top. Should the refrigerant container be made in sections, the ends of these sections might possibly abut the one against the other, but I prefer to lap them slightly as clearly seen in Fig. 2; there being however no necessity for making such joints between the sections water tight, and this need not be done unless 5 some special reason might arise therefor in which case the container would then be a single continuous container. The refrigerant container or the sections thereof may be directly attached to the under surface of the 10 top as by screws 14 and a reinforcing strip 15 of somewhat thicker material may be used if it should be so desired; or hangers 16 may be used and the upper edge of the container crimped as shown in Fig. 3 to simply hook 15 into these hangers. Should the hangers 16 be one continuous piece from end to end, rather than a number of hangers, as indicated by the lack of sectioning of this member in Fig. 3, the upper portion of the 20 container could be provided with holes as hereinbefore described, or the hanger similarly provided, but should a plurality of short hangers be used, openings may be left 25 between adjacent hangers, and the holes 10 in such case, be omitted.

Disposed below the central portion of the container is a drain trough 17 which may drain continuously from one end of the case to the other and be provided with a single 30 drain pipe 18, or may drain from the center to each end with duplicate oppositely disposed drain pipes, or even should it be so desired, have the drain pipe or pipes otherwise located. While the drain pipe 18 is 35 shown extended downwardly to drain outside of the refrigerator, it will of course be understood that some form of drain pan or pans may be used within the case to retain the water draining from the refrigerant and 40 thus secure such additional cooling effect as may result therefrom.

It will especially be noted that the moisture of condensation collecting on the outer 45 surface of the container, will run down, following along the surface owing to capillary attraction, and drop from the container at the lowest point thereof and into the drainage trough therebelow.

19 is a shelf disposed approximately flush 50 with or slightly below the bottom of the upper doors 3 and extending preferably from end to end of the case.

In using the refrigerator, the doors 7 in 55 the top are removed and crushed ice or other refrigerant is placed directly in the refrigerant container 8, 8^A etc., and is pushed both ways in the container to distribute the refrigerant more or less evenly therewithin. Food stuff may be placed on the shelf 19 60 through the upper doors 3, or be placed

directly on the bottom of the refrigerator through the lower doors 4, and when so placed may be seen through the glass front 2, so that where the refrigerator is used, as it ordinarily is, as a display refrigerator in 70 stores or the like, the customer will, largely because of the shape of the container, have an almost uninterrupted view of everything within the case.

It will be seen also, that the container 75 interferes very little, if at all, with placing or removing articles on or from the top shelf, and of course, not at all with the lower portion. It will likewise be seen, that the entire length of the refrigerator is available for 80 use as a storage compartment, and it will further be seen, that the refrigerant is disposed directly above the storage compartment and that therefore cold air therefrom drops directly downward, replacing warmer 85 air from the articles placed in the case, and that a direct circulation is thereby set up, which it is impossible to secure from cases in which the refrigerant is placed at the ends 90 of the case.

It will be seen that the size and shape of the ice container, ordinarily is such that the sections thereof must be introduced through the rear doors rather than through the top 95 openings, and that they must be and are supported from the top of the case. Also it will be seen that where hangers are used the sections are detachably secured within the case.

The drawings and description herein have 100 been drawn with ice in mind as a refrigerant, but it will be clearly seen and understood that should pipes containing a gas or liquid be disposed in the top of the refrigerator, the trough shaped container 105 shown would function equally well in collecting and concentrating the condensation drip therefrom in a drain trough and leading the water thus collected to a concentration point. The use of the term "container" or the terms "refrigerant container" 110 hereinafter in the claims is to be distinctly understood to cover not only an ice container, but one lying outside of, though not necessarily directly carrying a series of refrigerant pipes.

It will be distinctly understood, that the drawings herein are for purposes of illustration only, that various modifications 115 therein may be made, and that it is not my intention to limit myself to the specific details herein shown except as such details may be hereinafter set out in the claims.

Having now fully disclosed the invention, what is claimed is:—

1. A refrigerator, comprising a casing provided along its median longitudinal dimension with openings through the top of said casing, a cover for each of said openings, and a refrigerant container extending 130

longitudinally of said casing, said container being V shaped in cross section, with the upper edges of the legs of said V bent outward and downward forming inverted J shaped edges, J shaped hangers secured to the under side of the top of said casing, on each side of said openings, whereby the sides of said container may be detachably engaged with said hangers, and will depend downwardly therefrom and toward the center of said casing and present a minimum obstruction to viewing the contents of said casing.

2. A refrigerator, comprising a casing provided along its median longitudinal dimension with openings through the top of said casing, a cover for each of said openings, and a refrigerant container extending longitudinally of said casing, said container having the upper edges of its sides bent outward and downward, forming inverted J shaped edges, J shaped hangers secured to the under side of the top of said casing on each side of said openings whereby said container may be detachably engaged with said hangers and will depend downwardly and toward the center of said casing pre-

senting a minimum obstruction to viewing the contents of said casing.

3. A refrigerator, comprising a casing provided along its median longitudinal dimension with openings through the top of said casing, a cover for each of said openings, a refrigerant container extending longitudinally of said casing, said container being V shaped in cross section, with the upper edges of the legs of said V bent outward and downward forming inverted J shaped edges, J shaped hangers secured to the under side of the top of said casing on each side of said openings whereby the sides of said container may be detachably engaged with said hangers and will depend downwardly therefrom and toward the center of said casing and a narrow drain trough suspended below the lower portion of said V, whereby said container and trough will present a minimum obstruction to viewing the contents of said casing.

In testimony of the foregoing, I affix my signature.

FAY T. RODGERS.
